V. PELLEGRINO

EVAPORATOR FOR CARBURETORS

Filed May 5, 1925

INVENTOR.

Vincenzo Pellegrino
BY *John P. Murphy*
ATTORNEYS.

UNITED STATES PATENT OFFICE.

VINCENZO PELLEGRINO, OF RYE, NEW YORK.

EVAPORATOR FOR CARBURETORS.

Application filed May 5, 1925. Serial No. 28,278.

This invention relates to improvements in the mixtures supplied to the carburetors of engines and in the means for supplying the carburetors with these mixtures, and it is the principal object of the invention to supply to the carburetor a mixture of air and gas as well as of water vapor or steam in order to increase the explosive function and to supply a rich and well primed mixture.

Another object of the invention is the provision of a means for generating the vapor to be supplied to the air and gas mixture, by means of the heat of the exhaust.

A further object of the invention is the provision of a vapor or steam generator equipped with a controlling and safety valves, and a sifter.

A still further object of the invention is the provision of a vapor generator including a water tank equipped with means for controlling the supply of heat to the same.

These and other objects and advantages of my invention will become more fully known as the description thereof proceeds, and will then be specifically defined in the appended claims.

In the accompanying drawing forming a material part of this disclosure:

Fig. 1 is a side elevation of an engine cylinder and carburetor equipped with the novel vapor generator, constructed according to the present invention.

Fig. 2 is a section on line 2—2 of Figure 1.

Fig. 3 is a section on line 3—3 of Figure 2.

Fig. 4 is an enlarged detail sectional view of the heat supply controlling means, taken on the line 4—4 of Fig. 1.

An engine cylinder 10 of any well known type, is associated with a carburetor 11 of any customary construction, intake manifold 12, and exhaust pipe 13. The exhaust pipe 13 has attached to it by means of brackets 14 and 15, a water tank 16 with a filling opening closed by a removable cap 17, and a drain opening closed by a removable cap 18. A water vapor supply pipe 19 leads from the tank 16 to the carburetor and is equipped with a vapor supply controlling valve 20 and a safety valve 21 of any well known construction and type. A sieve or sifter 22 is provided at the outlet from tank 16 to pipe 19 for retaining the impurities contained in the water and vapor.

The heat supply from exhaust pipe 13 to tank 16 is controlled by means of a slide 23, having an operating knob 24 and a plurality of longitudinal slots 25 into which slidably engage the fingers 26 of a collar 27 secured to a flange 16^a of tank 16 by rivets 27' so that the heat supply surface, may be controlled, as desired by adjusting the slide 23 to vary the amount of opening 28 between the slide and the collar 27, so as to change the amount of contacting radiation surface. No openings exist for the passage of gases between pipe 13 and tank 16. The heat is transmitted by radiating through the material of pipe and tank, and the amount of radiation is controlled by slide 23 which varies the amount of radiation surface.

It is to be understood that while I have illustrated and described one example only of the practical embodiment of my invention, the same is subject to many changes in its general arrangement and in the construction of the minor details, such as fall within the scope of the appended claims without departure from the spirit and principle of my invention.

Having thus described my invention, what I claim as new, and desire to secure by Letters Patent, is:

1. In a vapor supply device for carburetors, having a water tank attached to the exhaust pipe of an engine, the combination of a flange depending from said tank, a collar formed with a plurality of fingers, attached to said flange, said collar abutting against said exhaust pipe, and a slide formed with longitudinal slots engaged by said fingers.

2. In a vapor supply device for carburetors, having a water tank attached to the exhaust pipe of an engine, the combination of a flange depending from said tank, a collar formed with a plurality of fingers, attached to said flange, said collar abutting against said exhaust pipe, and a slide formed with longitudinal slots engaged by said fingers, said slide being provided with an operating knob, whereby the radiation surface between said exhaust pipe and said collar may be varied.

In testimony whereof I have affixed my signature.

VINCENZO PELLEGRINO
